UNITED STATES PATENT OFFICE.

JOHN H. PILLINGS, OF HAMILTON, OHIO, ASSIGNOR TO HOOVEN AUTOMATIC TYPEWRITER CORPORATION, OF HAMILTON, OHIO, A CORPORATION OF NEW YORK.

TYPEWRITER-CARRIAGE-OPERATING MECHANISM.

1,360,789.

Specification of Letters Patent. Patented Nov. 30, 1920.

Application filed July 14, 1919. Serial No. 310,692.

To all whom it may concern:

Be it known that I, JOHN H. PILLINGS, a citizen of the United States, residing at Hamilton, in the county of Butler and State of Ohio, have invented a certain new and useful Improvement in Typewriter-Carriage-Operating Mechanism, of which the following is a full, clear, and exact description.

10 This invention is intended for use in and as a part of mechanism for automatically actuating the various parts of a typewriter in such sequence as is determined by the perforations in a perforated controller strip, to 15 the end that the typewriter may print form letters. The purpose of the mechanism in which the present invention is embodied is to automatically return the typewriter carriage to the starting position and to operate 20 the line spacing mechanism, in order that a new line may be printed in proper position upon the paper.

Mechanisms for automatically operating typewriters are, as may be supposed, constructed for use in connection with some commercial typewriters. The invention which forms the subject matter of this application is associated with an Underwood typewriter; but there is no reason why it 30 might not be adapted for use with any other form of typewriter. The typewriter frame is secured upon the frame which supports the mechanism for automatically operating the various parts of the typewriter.

35 The present invention involves the addition of a few simple parts to the typewriter, and the slight modification of certain other parts, as will appear; but neither these additions nor changes nor the connection of 40 the typewriter with the automatic operating mechanism interferes with the ordinary operation of the typewriter whenever that is desired.

In the drawings, Figure 1 is a side elevation of the present invention attached to a typewriter; Fig. 2 is a front elevation broken away, and Fig. 3 is a detail.

The particular typewriter operating mechanism employed must be of such general character that its various parts can be selectively operated in accordance with the perforations of a controller strip; but there are various mechanisms of this character which are capable of use in connection with the present invention. The drawing shows for

this purpose mechanism of this sort which is shown and described in my co-pending application, Serial No. 310,693, filed July 14, 1919; but it would not be at all difficult to employ for this purpose substantially the same mechanism which forms the subject matter of my prior Patent No. 1,174,090, or any other suitable mechanism for that matter.

The specific automatic mechanism shown involves the use of a rotating cylinder 10 carrying spurs 11 for engagement with the perforated controller strip S which runs over said cylinder. In the surface of this cylinder are numerous pockets 12 which will be covered by the unperforated part of the controller strip; and suitable mechanism will be required for slowly rotating the cylinder. Behind the cylinder are a plurality of vertically movable hangers 13 and associated mechanisms. Each hanger has a pawl 14 pivoted to it, which pawl extends forward; and its point normally rests upon the surface of the perforated controller strip. When a perforation comes beneath one of these pawls, the pawl drops through that perforation and engages in a pocket in the cylinder; wherefore, as the cylinder continues to rotate, the pawls will be displaced endwise in a rearward direction. This will cause a corresponding displacement of the associated hanger. The hanger carries on its rear side a shoulder 19 which, when the hanger is displaced rearwardly is carried beneath a vertically reciprocating depressor bar 16 which is associated with certain mechanism which keeps it constantly moving up and down. This depressor bar will in its downward movement strike the shoulder 19 on the rearwardly displaced hanger, and will move that hanger down. Two of these hangers 13, 13^a, are utilized in the present invention, one for causing the required operation of the mechanism which returns the carriage to its starting point; and for actuating the line spacing mechanism.

As before stated, however, it will be understood that any two movable parts which will be moved automatically at the proper time might be utilized for operating the present invention.

The carriage 20 of the typewriter is always provided with suitable line spacing mechanism; and this mechanism is always, so far as I know, operated by means of a lever 21, 110

which is also pivoted to the typewriter carriage. That lever is shown in the drawing, but no attempt has been made to indicate the line spacing mechanism which it operates, because that is a part of the typewriter to which the present invention is applied. There is, however, added to the typewriter in front of the carriage a transverse rock shaft 26. At its ends two arms 27 are fixed to this rock shaft; and the ends of these arms are connected by a bar 28 so as to make a rocking frame out of this rectangular structure. A bracket 22 is fixed to the frame of the typewriter carriage, and it carries a sheave 23 which is rotatably mounted. A cord 24 is connected at one end with the lever 21 for operating it. This cord runs over this sheave 23, and has a ring 29 fixed to its end, which ring embraces loosely the top rod 28 of the rocking frame referred to. Therefore, when the upper member of this rocking frame is rocked forward the cord will be pulled and the line spacing lever 21 will be operated. This action will take place regardless of the position of the typewriter carriage with respect to the typewriter frame, because the ring 29 slides freely on the bar 28 as the typewriter carriage is moved back and forth. To the rock shaft 26 which forms a part of this rocking frame an operating arm 30 is secured; and this arm is connected by a link 31 with one of the hangers 13^a, so that, as said hanger is automatically moved downward by the mechanism to which brief reference has been made, or by any suitable mechanism, this frame will be rocked and the line spacing mechanism operated.

As a part of the typewriter operating mechanism, there is a shaft 35 which is located at the left side of said mechanism and therefore extends from front to back, and is rotatably mounted in suitable bearings. Extending from side to side, that is, lying at right angles to this shaft 35, is another shaft 40, which is also suitably supported in bearings; and at the right end of this shaft a pinion 41 is fixed. This pinion is for engagement with a vertically sliding rack bar 42, which rack bar is connected by a cord or strap 43 with the typewriter carriage; said cord or strap passing over a guide sheave 44 mounted in a bracket 45 which is fixed to the typewriter frame. Evidently, therefore, the downward movement of this rack bar will move the carriage to the right until it arrives at the starting position. There are two freely rotatable grooved wheels 46 mounted on the frame of the typewriter operating mechanism, and they engage the rear plain edge of the rack bar and hold it in engagement with the pinion.

In order to rotate this pinion carrying shaft 40 this shaft has fixed to one end a bevel friction wheel 47. A reciprocally bevel

friction wheel 63 is mounted on the shaft 35 and has a tongue and groove sliding connection therewith so that it must rotate with said shaft. It is normally under the influence of a spring tending to push it forward and thereby to prevent its engagement with the disk. These two beveled disks form a satisfactory kind of friction clutch for transmitting motion from one of these shafts to the other. On the shaft is a sliding collar 64, and between this collar and the beveled wheel thereon is a spring. By moving the collar rearward the spring is compressed and it thrusts the bevel wheel rearward and into frictional engagement with the bevel wheel, and thereby the shaft is turned and the rack drawn down. To effect this clutching action automatically, and to hold the two shafts clutched together for the proper period of time, a three-arm rocker 50 is provided. One arm 51 is in the form of a fork which embraces the collar and is pivoted to the sides of the frame. The other arm 52 extends in a substantially horizontal direction beneath one of the hangers. The third arm extends in a substantially vertical direction, and serves as a latching arm 53. When a perforation in the controller strip comes to the functioning position it will cause through the mechanism which has been referred to the downward movement of this hanger. This will engage the arm of the rocker and rock the rocker with the result of clutching the two shafts together as stated. This movement of the rocker will likewise swing the latch arm 53 forward, and will carry a latch lug which is fixed to the arm in front of the end of a latch lever 54. This latch lever is pivoted to the typewriter frame. Its lower end normally engages the flat left face of said latch lug. When, as stated, the latch lug is moved forward it will pass out of engagement with the lever, whereupon the lever under the influence of a spring will move back of this latch lug and prevent the return movement of the rocker. Therefore, whenever, through the operation of the mechanism described, the clutch connects the two shafts, that connection will be maintained until by the operation of the mechanism now to be described the two shafts become unclutched. While they are clutched together, the carriage will be moved to the right back to its starting position.

In the typewriter there is a transversely extended rod 65 to which the carriage return stop is fixed. Normally this rod has no endwise movement. In the present construction, however, it is allowed a certain endwise movement. Its left end projects through the supporting frame member, and it has an enlarged head 66 which lies outside of, that is to the left of the upper end of this latch lever. When the carriage has, by the described mechanism, been returned

to its starting position, it will strike a strip fastened to this rod, and will move the rod endwise slightly. In this endwise movement, however, the head thereon will engage 5 the latch lever and rock it so that its lower end is released from engagement with the latch lug on the rocker. Thereupon the spring will push the beveled clutch collar forward, and it, acting through the spring, 10 will push the sliding collar forward and thereby the rocker will be rocked to its normal position. The two shafts are now unclutched. When the latch lever has moved to the position stated the lower end of the 15 trip lever will move into contact with the left face of the lug. The parts are now restored to their normal position and everything is in readiness to begin printing of a new line. As soon as the carriage makes its 20 first movement to the right the pressure on the rod will be released and the spring associated therewith will move it to the left, and therefore restore it to the normal position shown in the drawing, in which it is 25 ready to again act in the manner stated.

Various changes may be made in the specific embodiment of the invention shown and described herein, provided the means stated in any of the following claims or the 30 equivalents of such stated means be employed.

Having described my invention, I claim:—

1. In typewriter operating mechanism, the combination with the typewriter carriage of 35 a guided sliding rack bar, a flexible connector connecting said carriage and rack bar, a pinion engaging said rack bar, a driving shaft, friction clutch mechanism for connecting said driving shaft and pinion, mechanism for automatically causing the clutch engaging movement of said clutch mechanism, an automatic latch for holding the clutch in the clutch engaging position, means operated by the typewriter carriage 40 for withdrawing said latch, and means to automatically move the clutch mechanism in the clutch releasing direction when the latch is withdrawn.

2. In typewriter operating mechanism, the 50 combination with the typewriter carriage, mechanism for returning said carriage to its starting point, clutch controlled mechanism for actuating said carriage return mechanism, and spring-actuated transversely movable sliding bar having a projection which lies in the path of a part of the typewriter carriage as said carriage moves toward its starting position, a head on one projecting end of said bar, clutch operating mechanism, 55 a latch lever which at its lower end may engage said clutch operating mechanism to hold the clutch in the clutching position, the upper end of said lever being projected into a position to be engaged by the head on the 60 sliding bar whereby the lever will be moved 65

in the latch releasing direction when the sliding carriage on its return movement moves said sliding bar.

3. In typewriter operating mechanism, in combination with the typewriter carriage, a 70 rotatable shaft, means actuated by said shaft for returning the typewriter carriage to its starting position, a beveled friction disk fixed to said shaft, a driving shaft, a friction disk slidably mounted upon and having a tongue and groove connection with the driving shaft and adapted to engage the friction disk on the first mentioned shaft, a rocker having an arm adapted to move the sliding friction disk along its 75 shaft and into engagement with the first mentioned friction disk, said rocker having a second arm, means controlled by a perforated controller strip for engaging said arm to rock the rocker, a latch for preventing the return movement of said rocker after it has been so moved, and mechanism operated by the typewriter carriage as it returns to its starting position for releasing 80 said latch.

4. In typewriter operating mechanism, in combination with the typewriter carriage, a rotatable shaft, means actuated by said shaft for returning the typewriter carriage to its starting position, a beveled friction 95 disk fixed to said shaft, a driving shaft, a friction disk slidably mounted upon and having a tongue and groove connection with the driving shaft and adapted to engage the friction disk on the first mentioned shaft, a 100 rocker having an arm adapted to move the sliding friction disk along its shaft and into engagement with the first mentioned friction disk, said rocker having a second arm, means controlled by a perforated controller strip for engaging said arm to rock the rocker, a latch for preventing the return movement of said rocker after it has been so moved, and mechanism operated by the typewriter carriage as it returns to its starting position for releasing 105 said latch, and a spring for moving said sliding disk out of contact with the other friction disk.

5. In typewriter operating mechanism, the combination with the typewriter carriage, a rotatable shaft, means actuated thereby for returning the carriage to its starting position, a bevel friction disk fixed to said shaft, a driving shaft, a bevel friction disk having a tongue and groove sliding connection with the driving shaft, a sliding clutch sleeve upon said shaft, a spring interposed between said clutch sleeve and a sliding friction disk, mechanism for automatically moving said clutch sleeve along 115 the shaft so as to compress said spring and thereby force the associated friction disk into operative contact with the first mentioned friction disk.

6. In typewriter operating mechanism, 120

the combination with the typewriter carriage, a rotatable shaft, means actuated thereby for returning the carriage to its starting position, a bevel friction disk fixed 5 to said shaft, a driving shaft, a bevel friction disk having a tongue and groove sliding connection with the driving shaft, a sliding clutch sleeve upon said shaft, a spring interposed between said clutch sleeve, 10 and said bevel friction disk, mechanism for automatically moving said clutch sleeve along the shaft so as to compress said spring and thereby force the associated friction disk into operative contact with the first 15 mentioned friction disk, an automatic latch for holding said sliding sleeve in the spring compressing position, and mechanism operated by the typewriter carriage on its return movement for releasing said latch.

20 7. In typewriter operating mechanism, the combination with the typewriter carriage, a rotatable shaft, means actuated thereby for returning the carriage to its starting position, a bevel friction disk fixed 25 to said shaft, a driving shaft, a bevel friction disk having a tongue and groove sliding connection with the driving shaft, a collar fixed to said shaft, a spring embracing the shaft and compressed between it and 30 said friction disk, a sliding clutch sleeve upon said shaft, a spring interposed between said clutch sleeve, and said bevel friction

disk, mechanism for automatically moving said clutch sleeve along the shaft so as to compress said spring and thereby 35 force the associated friction disk into operative contact with the first mentioned friction disk.

8. In typewriter operating mechanism, the combination of the line spacer lever of 40 the typewriter carriage, a guide sheave fixed to the typewriter carriage, a rocking frame having a transversely extended bar at its movable end, a ring loosely embracing said bar, a cord connecting said ring with said 45 line spacer lever, and mechanism for selectively rocking said rocking frame.

9. In typewriter operating mechanism, the combination of the line spacer lever of 50 the typewriter carriage, a guide sheave fixed to the typewriter carriage, a rocking frame having a transversely extended bar at its movable end, a ring loosely embracing said bar, a cord connecting said ring with said 55 line spacer lever, an operating arm fixed to said frame, a vertically movable hanger connected with said arm, and means controlled by a perforated controller strip for automatically moving said hanger downward.

In testimony whereof I hereunto affix my signature.

JOHN H. PILLINGS.
